UNITED STATES PATENT OFFICE.

HENRY H. EVERSEN, OF MERIDEN, CONNECTICUT, ASSIGNOR TO WILCOX & EVERSEN, OF SAME PLACE.

DESIGN FOR A SPOON.

SPECIFICATION forming part of Design No. 30,715, dated May 9, 1899.

Application filed March 1, 1899. Serial No. 707,415. Term of patent 3½ years.

To all whom it may concern:

Be it known that I, HENRY H. EVERSEN, of Meriden, in the county of New Haven and State of Connecticut, have invented a new 5 Design for Spoons; and I do hereby declare the following, when taken in connection with the accompanying drawings and the letters of reference marked thereon, to be a full, clear, and exact description of the same, and which 10 said drawings constitute part of this specification, and represent, in—

Figure 1, a face view of a spoon embodying my design; Fig. 2, a reverse view of the same.

This invention relates to the design for a 15 spoon; and it consists in the configuration as hereinafter described, and shown in the accompanying illustration.

In the bowl A of the spoon is a picture representing a rear view of the mansion-house at 20 Mount Vernon. At the juncture of the bowl and handle is a wreath B, inclosing pictures of George Washington and his consort, Mar-

tha Custis Washington. Above the wreath the handle gradually expands and is bordered by long scrolls C. The outer end of the handle is enlarged, and on its surface is engraved a perspective face view of the mansion-house at Mount Vernon. This end is bordered by scrolls D E and surmounted by a crest F. The reverse of the handle contains within the 30 wreath B an American flag G and the outer end contains a picture of the tomb of Washington at Mount Vernon, all as shown in the accompanying illustrations.

I claim—

The design for a spoon as herein shown and described.

In testimony whereof I have signed this specification in the presence of two subscribing witnesses.

HENRY H. EVERSEN.

Witnesses:

FRARAY HALE,
LOUIS E. WILCOX.
